UNITED STATES PATENT OFFICE.

ERNEST A. PANNIER, OF CHICAGO, ILLINOIS.

WATER-HEATER.

No. 824,808.

Specification of Letters Patent.

Patented July 3, 1906.

Application filed July 14, 1905. Serial No. 269,713.

To all whom it may concern:

Be it known that I, ERNEST A. PANNIER, a citizen of the United States, residing at Chicago, in the county of Cook and State of Illinois, have invented new and useful Improvements in Water-Heaters, of which the following is a specification.

This invention is a water-heater adapted particularly for use in connection with a hot-water or steam heating system, and provides means whereby the heated water or steam used in the heating system may be utilized for heating water for the water-supply system of the house or building.

The invention is particularly characterized by a cheap and improved construction of the heater, as will more fully appear from the following description.

In the accompanying drawings, Figure 1 is a side elevation of the heater connected to a tank and boiler and illustrating one use to which the heater may be put. Fig. 2 is a central vertical section of the heater. Fig. 3 is a section on line 3 3 of Fig. 2.

Referring specifically to the drawings, 6 indicates a steam or hot-water boiler of any desired construction, and in the utilization of the device for domestic purposes it is intended that this boiler shall be a part of the heating system. The boiler is connected by pipes 7 and 8 to the water-heater, as hereinafter described, these pipes being controlled by valves 7^a and 8^a, and the water-heater is connected by pipes 9 and 10 to the water-tank 11, which is a part of the water-supply system for the house or other building.

The water-heater consists of an outer casting 12, which may conveniently be made of iron pipe of suitable diameter—say three or four inches. This pipe is threaded at both ends to screw into the upper and lower headers. The upper header consists of a cap 13, into the top of which the pipe 7 is screwed, and the rim of this cap is interiorly threaded to receive a circular plate 14, which has a depending rim 15 interiorly threaded to receive the upper end of the pipe 12. The plate 14 has a series of holes 16, preferably arranged around a central cone 17, which acts as a distributor. The holes 16 receive the ends of the interior pipes 18, which are expanded therein.

The lower header 19 is cast in one piece and has a central circular chamber 20, the top of which is provided with taps 21, corresponding to the holes 16, and the lower ends of the

pipes 18 are screwed in the said taps. The bottom of the header 19 extends out beyond the side wall of the chamber 20 and is provided with an annular flange 22, which is 60 spaced from the side wall of the chamber 20 and is interiorly threaded to receive the lower end of the outer pipe 12.

The pipes 9 and 10 are tapped into the side wall of the pipe 12, and all the connecting-pipes are provided with the necessary unions, elbows, &c. The cap 13 is or may be provided with lugs 23, whereby the heater may be hung from a beam or joist, or the heater may be supported from below by any suitable stand.

In assembling the parts the header 19 and plate 14 are screwed on opposite ends of the outer pipe 12. The inner pipes 18 are then inserted and screwed into the taps 21 and 75 then expanded over the plate 14. The cap 13 is then screwed on and the proper connections made.

The hot water or steam from the boiler is supplied through the pipe 7 and circulates 80 down through the pipes 18 and the headers and back through the pipe 8 to the boiler. The water to be heated circulates from the tank through the pipe 10 and up through the outer tube 12 and around the inner tubes 18 85 and back to the tank through the pipe 9 and is heated by radiation from the headers and the pipes 18.

Without material modification the apparatus may be used as a cooler for water or 90 other fluids by providing a circulation of cold fluid through the device.

What I claim as new, and desire to secure by Letters Patent, is—

A water-heater comprising an outer cylindrical casing having inlet and outlet pipes, headers on opposite ends of the casing, connecting-pipes between the headers, within the casing, one header having two parts, one consisting of a plate having holes for the said 100 connecting-pipes and a threaded ring into which the end of the casing is screwed, and the other part consisting of a cap screwed onto the plate.

In testimony whereof I have signed my 105 name to this specification in the presence of two subscribing witnesses.

ERNEST A. PANNIER.
